Des. 182,777
Patented May 13, 1958

182,777

ADJUSTABLE SERVICE DISH HOLDER

Ray E. Troendly, Elkton, Oreg., assignor to Troendly Illinois Corporation, Melrose Park, Ill., a corporation of Delaware

Application January 25, 1957, Serial No. 44,613

Term of patent 14 years

(Cl. D44—10)

Fig. 1

Fig. 2

Fig. 3

Fig. 1 is a side elevational view of an adjustable service dish holder, showing my new design;

Fig. 2 is a top plan view; and

Fig. 3 is an end elevational view.

I claim:

The ornamental design for an adjustable service dish holder, as shown.
